CLAIM

The ornamental design for a medical device connector, as shown and described.

DESCRIPTION

FIG. 1 is a front right top perspective view of a first embodiment of a medical device connector showing our new design;

FIG. 2 is a front elevation view of the first embodiment; FIG. 3 is a back elevation view of the first embodiment; FIG. 4 is a left side elevation view of the first embodiment; FIG. 5 is a right side elevation view of the first embodiment; FIG. 6 is a top plan view of the first embodiment; FIG. 7 is a bottom plan view of the first embodiment; FIG. 8 is a front right top perspective view of a second embodiment of a medical device connector showing our new design;

FIG. 9 is a front elevation view of the second embodiment; FIG. 10 is a back elevation view of the second embodiment; FIG. 11 is a left side elevation view of the second embodiment;

FIG. 12 is a right side elevation view of the second embodiment;

FIG. 13 is a top plan view of the second embodiment; FIG. 14 is a bottom plan view of the second embodiment; FIG. 15 is a front right top perspective view of a third embodiment of a medical device connector showing our new design;

FIG. 16 is a front elevation view of the third embodiment; FIG. 17 is a back elevation view of the third embodiment; FIG. 18 is a left side elevation view of the third embodiment;

(Continued)

FIG. 19 is a right side elevation view of the third embodiment;
 FIG. 20 is a top plan view of the third embodiment; and,
 FIG. 21 is a bottom plan view of the third embodiment.
 The broken lines shown in the drawings illustrate portions of the medical device connector that form no part of the claimed design.
